UNITED STATES PATENT OFFICE.

GEORGE NORMAN, OF SMALL HEATH, BIRMINGHAM, ENGLAND, ASSIGNOR TO THE BIRMINGHAM SMALL ARMS COMPANY LIMITED, OF BIRMINGHAM, ENGLAND.

AUTOMATIC FIREARM.

Application filed November 17, 1926, Serial No. 148,954, and in Great Britain July 9, 1925.

This invention relates to improvements in automatic fire-arms of the type having a fixed barrel and wherein a rotary and reciprocating breech bolt is provided with locking abutments adapted to engage with locking abutments in the breech body or receiver, and a return spring is interposed between the breech bolt and an end cap mounted on the breech body, which spring is compressed by the recoiling movement of the breech bolt and energy is thereby stored or conserved in the spring and then utilized to effect the closing of the breech mechanism. The invention relates more particularly to a safety device intended to prevent rotary or unlocking movement of the breech bolt and movement or release of the trigger mechanism when the breech mechanism is in its closed position and the trigger mechanism cocked ready for firing, and has for its object to provide means for effecting the simultaneous locking of the breech bolt and trigger mechanism, which is simple in construction and adapted to be readily actuated by the fore-finger of the hand which grips the gun.

The invention contemplates an automatic fire-arm of the type referred to, wherein a safety device, for preventing rotary or unlocking movement of the breech bolt and movement or release of trigger mechanism, may be readily actuated by the shooter's fore-finger when gripping the gun in the position ready for firing, which safety device comprises a safety bar or spindle rotatably mounted and longitudinally disposed in the side of the breech body, and having a projection at its front end and gaps in its sides, the said projections and gaps being so arranged and disposed that a partial rotation of the bar will bring the projection into engagement with a groove in the periphery of one of the locking abutments on the breech bolt, and also bring a narrow gap in the said bar into engagement with a lug or projection on the sear of the trigger mechanism, whereby the said parts are locked and movement of same is thus prevented. By a reverse partial rotation of the said safety bar, a cut-away part at the end thereof, and a wide gap in the side of the bar, are brought respectively opposite to the locking lug on the bolt and the projection on the sear, and permit of the firing of the gun and the opening of the

breech mechanism. On the rear end of the aforesaid safety bar, at a position near to the trigger, an operating lever and spring detent are mounted, which lever and detent are arranged and adapted to permit of movement of the said lever to its operative or inoperative positions by means of the shooter's finger, while the gun is held ready for firing.

In order that the invention may be clearly understood and readily carried into effect, I will describe same with reference to the accompanying illustrative drawings, in which:

Figures 1 and 2 are, respectively, a part sectional elevation, and a part sectional plan view of an automatic fire-arm embodying a safety device constructed in accordance with and embodying the features of this invention.

Figure 3 is a transverse section taken on line 3—3, Figure 1.

Figure 4 is a transverse section taken on line 4—4, Figure 1.

Figures 5, 5^a, 5^b and 5^c are, respectively, a side elevation, an end view, and transverse sectional views at A and B (Figure 5) of the safety rod.

Figures 6, 6^a and 6^b are, respectively, an end view, a side elevation and a plan view of the safety rod operating arm or lever.

Figures 7, 7^a and 7^b are, respectively, a front elevation, a sectional side elevation and a plan view of the sear.

Figure 8 is a side elevation of the rear end of the breech bolt.

Figure 9 is an elevation of the rear end of the breech bolt.

According to one practical embodiment of this invention, as illustrated in the accompanying drawings, the safety bar 1 is formed of a round bar which is rotatably mounted in an approximately semi-cylindrical longitudinal groove 2 formed in one side of the inner face of the breech body 3 and disposed at a position about forty-five degrees below the horizontal, and extending through a section of the interrupted screw threads 4 in the end of the body 3 in which is mounted the end cap 5, the latter being adapted, when in position, to longitudinally confine the safety bar 1 in its operative position in the breech body 3. The breech bolt 7 has on its periphery a plurality of locking abutments 6 which, when said bolt is partially rotated,

100

105

105

engage a plurality of complementary locking abutments 10 formed on the interior of the breech body to lock the bolt 7 against longitudinal movement. The firing mechanism comprises a firing pin which is urged forwardly by a spring and is provided with a bent for engagement by a nose of the sear 8. The sear 8, which is of substantially bell-crank form, is pivotally mounted on the breech body in advance of the trigger 17 and has one arm which forms its bent-engaging nose projecting upwardly through a slot in the breech body to engage with the bent on the firing pin and has its other arm dependent below its pivot and engaged by one end of a link, of which the other end is connected to or associated with the upper end of the trigger 17 pivotally connected between its upper and lower ends to the rear portion of the breech body. The sear 8 has an additional arm or lug 12 which extends upwardly therefrom into the breech body substantially at a right angle to its bent-engaging arm for a purpose which will presently appear.

A portion of the periphery of the bar 1 is cut away at its forward end, as at 13, thus forming a segmental portion and a recess. The breech bolt 7 has a substantially semi-cylindrical groove 9 in its periphery at or adjacent its rear end and so located relatively to its locking abutments 6 that, when the bolt is partially rotated to move its locking abutments 6 into engagement with the locking abutments 10 of the breech body, said groove 9 will be opposite the longitudinal groove 2 of the breech body, at which time the bar 1 may be partially rotated to cause its segmental portion to enter said groove 9 and thus lock the breech bolt against rotation. But when the bar 1 is partially rotated in the opposite direction its segmental portion is moved out of the recess 9 and its cut-away portion is brought opposite to said recess 9, at which time the breech bolt may be partially rotated to disengage its locking abutments 6 from the locking abutments 10 of the breech body.

The bar 1 also has a notch 11 in its periphery so located relatively to the cut-away portion 13 that, when the locking abutments 6 of the breech bolt 7 are in engagement with the locking abutments 10 of the breech body and the bar 1 is partially rotated to cause its segmental portion to enter the groove 9 of the breech bolt, the vertically disposed lug or projection 12 on the sear 8 of the trigger mechanism will enter said notch with its rear edge bearing against the rear end of said notch and thus lock the trigger mechanism against actuation. The bar also has in its periphery an additional notch 14 which merges into the notch 11 at substantially a right-angle to the latter and of which the rear end extends rearwardly of the rear

end of the notch 11. The notch 14 is in substantially longitudinal alignment with the cut-away portion 13, so that, when the bar 1 is partially rotated to bring its cut away portion 13 opposite to the recess 9 of the locking bolt, the notch 14 will be brought opposite to the lug or projection 12 of the sear 8, thus permitting the sear 8 to be rocked on its pivot by actuation of the trigger 17 to disengage its bent-engaging nose 75 from the bent of the firing pin.

The operating arm or lever 15 of the safety bar 1 lies in a slot in the side of the breech body 3 and in the fore end stock 16 adjacent to the trigger 17, in Figures 2 and 4, to permit of it being easily manipulated by a finger of the shooter. It comprises an inner boss 18 having a hole through which the safety bar 1 extends and has a notch 19 to receive a pin or projection 20 on the said bar whereby the arm 15 is fixed in operative position on said bar. The arm 15 is curved and its end is preferably knurled to facilitate the movement of same.

A transverse slot 21 is formed in the boss 18 and through part of the length of the operating lever 15, thus producing a springy limb or member 22 on the outer face of which is formed a projection 23 adapted to yieldingly engage with notches or detents formed in one side of the slot in the breech body 3 in which the said lever is mounted, and thus serves to hold the lever in either its operative or inoperative position.

Having fully described my invention, what I desire to claim and secure by Letters Patent is:—

1. In a firearm comprising a breech body, a breech bolt in said body having means adapted, when said bolt is partially rotated on its axis, to engage complementary means in the breech body for locking said bolt in closed position and a firing pin longitudinally movable in the breech body, a sear for holding said firing pin in cocked position and trigger for releasing said sear, means for simultaneously locking the breech bolt against rotation and the sear against release, said means comprising a rod extending longitudinally of the breech body and mounted to rock at a right angle to its length, said rod having portions movable, respectively, into and out of the path of rotary movement of the breech bolt and into and out of the path of movement of a part of the sear when the locking means of the breech bolt are in engagement with the locking means of the breech body and said rod is rocked in opposite directions, and means projecting exteriorly of the breech body adjacent the trigger for rocking said rod.

2. A firearm according to claim 1 wherein the portion of the rod which is movable into and out of the path of rotary movement of the locking bolt is substantially semi-cylindrical.

drical in cross-section and the breech bolt has on its periphery a substantially cylindrical recess into and out of which the substantially semi-cylindrical portion of the rod is movable.

3. A firearm according to claim 1 wherein the part of the sear into the path of which a portion of the rod moves consists of an arm carried by the sear, and the portion of the rod which is movable into said path comprises a shoulder formed on the periphery of said rod.

4. A firearm according to claim 1 wherein the breech body has a slot in its wall adjacent the trigger and the means for rocking the rod comprises a lever extending through said slot.

5. A firearm according to claim 1 wherein the breech body has a slot in its wall adjacent the trigger, and the means for rocking the rod comprises a boss secured to the rod and mounted in said slot and a lever carried by said boss.

6. A firearm according to claim 1 wherein the breech body has a slot in its wall adjacent to the trigger and the means for rocking the rod comprises a boss secured to the rod and mounted in said slot, and having means engageable with one of the walls of said slot for holding the rod in operative or inoperative position.

7. A firearm according to claim 1 wherein the breech body has an internal groove in its wall parallel to the axis of rotation of the breech bolt and in which the rod is mounted to rock.

8. A firearm according to claim 1 wherein the wall of the breech body has an internal longitudinal groove in which the rod is mounted to rock and a slot intersecting said groove at a right angle to the latter adjacent the trigger, and the means for rocking the rod comprises a boss engaging the rod and rotatable in said slot.

9. A firearm according to claim 1 wherein the breech body has a slot radially disposed relatively to the breech bolt and the means for rocking the rod comprises a radially slotted boss engaging the rod and having one

of its ends frictionally bearing against one 50 of the end walls of said slot.

10. In a firearm comprising a breech body, a breech bolt rotatable in said body and having means adapted, when said bolt is partially rotated, to engage complementary means 55 in the breech body for locking the bolt in closed position, a firing pin longitudinally movable in the breech body, a sear engageable with the firing pin to hold the latter in cocked position, and a trigger for releasing 60 said sear, means for simultaneously securing the breech bolt against rotation and the sear against release, said means comprising a rod extending longitudinally of the breech body and mounted to rock at a right angle to its 65 length, said rod having means movable into and out of engagement with the breech bolt when the breech bolt is in locked position and said rod is rocked in opposite directions, said rod also having in its periphery a pair 70 of notches arranged substantially at a right angle to one another, one of said notches adapted, when said rod is rocked to engage the locking bolt, to straddle and prevent movement of a portion of the sear and the 75 other of said notches being of a length and depth sufficient to receive and permit movement of said portion of the sear when said rod is rocked out of engagement with the locking bolt, and means adjacent the trigger 80 for rocking said bar.

11. A firearm according to claim 10, wherein the breech body has a slot adjacent the trigger and substantially at a right angle to the rod, and the means for rocking the rod 85 comprises a lever-carrying boss secured to said rod and rotatable in said slot, said boss having a radial slot forming a limb tending to move toward one wall of said slot, said limb having a projection on its outer face 90 and said wall having depressions to respectively receive the projection of said limb when said boss is rotated to rock the rod into operative and inoperative positions.

In testimony whereof I have hereunto set 95 my hand.

GEORGE NORMAN.
